(57) **CLAIM**

The ornamental design for a shaving razor cleaning device, as shown and described.

DESCRIPTION

FIG. 1 is a top, front, left perspective view of a shaving razor cleaning device, showing my new design;

FIG. 2 is a top, front, right perspective view thereof;

FIG. 3 is a top, rear, right perspective view thereof;

FIG. 4 is a top, rear, left perspective view thereof;

FIG. 5 is a bottom, front, right perspective view thereof;

FIG. 6 is a bottom, front, left perspective view thereof;

FIG. 7 is a bottom, rear, left perspective view thereof;

FIG. 8 is a bottom, rear, right perspective view thereof;

FIG. 9 is a front view thereof;

FIG. 10 is a rear view thereof;

FIG. 11 is a right side view thereof;

FIG. 12 is a left side view thereof;

FIG. 13 is a top view thereof;
